CLAIM

The ornamental design for a display screen or portion thereof with a graphical user interface, as shown and described.

DESCRIPTION

FIG. 1 is a front view of a first embodiment of a display screen or portion thereof with a graphical user interface. FIG. 2 is a front view of a second embodiment of a display screen or portion thereof with a graphical user interface. FIG. 3 is a front view of a third embodiment of a display screen or portion thereof with a graphical user interface; and, FIG. 4 is a front view of a fourth embodiment of a display screen or portion thereof with a graphical user interface. The broken lines showing a mobile device illustrate environmental structure and form no part of the claimed design. All other broken lines in the drawings depict portions of a graphical user interface that form no part of the claimed design.
